A. D'ASCENZO

METHOD FOR REMOVING GAS AND DUST FROM MINES

Filed April 3, 1925

UNITED STATES PATENT OFFICE.

ANGELO D'ASCENZO, OF DENVER, COLORADO.

METHOD FOR REMOVING GAS AND DUST FROM MINES.

Application filed April 3, 1925. Serial No. 20,504.

To all whom it may concern:

Be it known that I, ANGELO D'ASCENZO, a subject of the King of Italy, residing at Denver, in the county of Denver and State 5 of Colorado, have invented certain new and useful Improvements in Methods for Removing Gas and Dust from Mines, of which the following is a specification.

This invention is a method for removing 10 gas and dust from mines.

With the usual system of mine ventilation, fixed pipes or passages are required for conducting fresh air into the mine, and for leading the vitiated air and gas out of the 15 mine. The principal object of this invention is to dispense with the use of such fixed inlet and outlet pipes or passages, the expense of installation and maintenance of which is very considerable.

20 In accordance with the method of this invention, the gas is collected from various parts of the mine, is compressed into a smaller volume, into a pressure flask, for example, and the flasks are shipped out of the mine 25 from time to time. The dust collected may be put into bags or other containers, and these shipped out of the mine.

The preferred form of apparatus for carrying out the method comprises essentially 30 a portable unit, mounted on a wheeled truck that can readily be run to any desired part of the mine. On the truck there is mounted suction producing means, with which are connected two or more flexible suction pipes, 35 one for reaching to the roof of the mine, for collecting the gas which usually collects there, and the other for reaching to the floor of the mine for collecting dust.

40 The collected gas and dust are preferably kept separate. The gas is delivered to a compressor, which compresses it into smaller volume, into a pressure flask. These flasks may be shipped out of the mine from time to time. The dust may be bagged, or otherwise disposed of.

The suction means preferably comprises two fans mounted in separate casings on a common shaft. One motor is preferably used to drive both fans and the compressor.

50 Further details of the invention and additional features of construction and operation will be apparent from the accompanying drawing, illustrating one possible embodiment of apparatus for carrying out

the invention. These drawings are more or less diagrammatic.

In these drawings,

Fig. 1 is a side view of the apparatus, and Fig. 2 is a plan view of the same.

Referring more in detail to these drawings 60 in which similar reference characters indicate similar parts, the roof and floor of the mine are indicated at R and F respectively.

The apparatus comprises a truck 1 provided with wheels 2, which may be flanged 65 for running on the usual mine tracks 3, or which may be wheels of a suitable type for running on the floor of the mine. Mounted on the truck is an electric motor 4 which drives a shaft 6 mounted in bearings 7. 70 Fixed on the shaft 6 is a pair of suction fans 8 and 9 mounted in separate casings 11 and 12 respectively. A partition 13 is positioned between the fans, so that the materials sucked in by them are kept separated. 75

A flexible suction pipe 14, provided with the usual nozzle 15 is connected to one fan casing, here shown as casing 11. This suction pipe may be used for collecting gas from the roof of the mine, where it usually 80 collects, although of course it is made long enough to reach the floor of the mine in case the gas should collect there. The pipe 14 is preferably manually operated.

The gas collected by pipe 14 is led into 85 casing 11 and thence delivered to a pipe 16 provided with a valve 17 and a branch pipe 18 having a valve 19. The pipe 18 delivers to gas compressor 21, which compresses it to a high pressure and delivers it, through a 90 pipe 22, to any one of a plurality of pressure flasks 23, provided with the usual valves 24.

The compressor 21 may be driven from motor 4 by a pulley wheel 26 on shaft 6, which drives a belt 27 and pulley wheel 28 95 on the shaft of the compressor.

A second flexible suction pipe 31 having a nozzle 32 is connected to the other fan casing, here casing 12. The pipe 31 is long enough to reach to the floor or roof as desired, but is primarily used for collecting dust from the floor of the mine. The collected dust is discharged into a pipe 33 and pipe 34, having a valve 35, and a side outlet pipe 36, provided with a valve 37. Pipe 36 100 delivers the dust into a dust collecting bag 38; the dust filled bags may be periodically shipped out of the mine. The dust could be 105

otherwise disposed of through opening valve 35. The pipe 31 is preferably manually operated.

The truck of course carries a number of flasks and bags for the gas and dust, so when one is filled, another may be substituted.

It will therefore be seen that this apparatus will collect gas and dust from a mine, and will put the gas and dust in separate containers which may be periodically shipped out of the mine. The gas and dust may thus be removed from the mine by running the truck 1 through the mine as often as needed. The expense of installation and maintenance of gas pipes and passages is entirely eliminated.

It should be understood that the drawing is illustrative of one way of carrying out the invention, and that the invention is not to be limited to the specific details here shown, but may be carried out in other ways.

Having thus described my invention, what I claim as new and desire to secure by Letters Patent:—

1. A method for removing gas and dust from a mine without the use of fixed pipes

or passages, comprising separately and simultaneously collecting the gas and dust, storing the collected dust in a container, compressing the gas into a storage container, and periodically shipping the dust and gas containers out of the mine.

2. The method of removing dust and gas from mines without the use of a fixed piping system, comprising running a car through the mine, simultaneously collecting gas and dust from the mine with a plurality of suction nozzle devices carried by the car, storing the collected gas and dust in appropriate containers on the car, and periodically shipping the containers out of the mine.

3. The method of removing dust and gas from mines without the use of a fixed piping system, comprising running a car through the mine, simultaneously collecting gas and dust from the mine with a pair of suction nozzle devices carried by the car, compressing the gas, storing the collected gas and dust in containers carried by the car, and periodically shipping the containers out of the mine.

In testimony whereof I affix my signature.

ANGELO D'ASCENZO.
